Primary Examiner — Keith J Wilson(74) *Attorney, Agent, or Firm* — Wenderoth, Lind & Ponack, L.L.P.(57) **CLAIM**

The ornamental design for a shrink wrap gun, as shown.

DESCRIPTION

FIG. 1 is a perspective view of a shrink wrap gun embodying my design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the shrink wrap gun which form no part of the claimed design.

1 Claim, 7 Drawing Sheets(56)
